UNITED STATES PATENT OFFICE.

DANIEL W. ALBRIGHT, OF CEDAR RAPIDS, IOWA.

BICYCLE-SUPPORT.

SPECIFICATION forming part of Letters Patent No. 564,184, dated July 14, 1896.

Application filed January 7, 1895. Serial No. 534,163. (No model.)

To all whom it may concern:

Be it known that I, DANIEL W. ALBRIGHT, a citizen of the United States, residing at Cedar Rapids, in the county of Linn and State 5 of Iowa, have invented certain new and useful Improvements in Bicycle-Supports; and I do hereby declare the following to be a full, clear, and exact description of the invention, such as will enable others skilled in the art 10 to which it appertains to make and use the same.

The object of my invention is to produce a bicycle-support which may be attached to a wheel without altering the same and which 15 when attached will present a neat appearance.

A further object of my invention is the production of a support of such construction and arrangement with respect to the bicycle that 20 it may be readily released by the rider without dismounting and which when so released will automatically assume its proper position for supporting the wheel.

In the accompanying drawings, Figure I is 25 a side elevation of a bicycle with my support attached and in its normal position, the supporting position of the same being shown in dotted lines. Fig. II is a rear elevation of the bicycle, showing the support swung down 30 to the supporting position. Fig. III is a side elevation, on an enlarged scale, of the support and mechanism for attaching it to the cycle-frame. Fig. IV is a view of the head of the support at right angles to the position shown 35 in Fig. III. Fig. V is a vertical longitudinal section of Fig. IV. Fig. VI is a section on the line $x-x$ of Fig. III. Fig. VII is a detail view of the retaining-hook D and its securing mechanism. Fig. VIII is a detail view of a 40 modified form of the lower ends of the legs of the support.

Referring to the letters on the drawings, A indicates the rear brace-rod of the bicycle, extending, as usual, from the upper rear angle 45 of the frame to the rear axle, and B indicates a clamping-collar provided with an ordinary clamping-screw G and longitudinally adjustable upon the brace-rod A.

The collar B, for a purpose hereinafter ap- 50 parent, is secured to the brace-rod in such position as to be substantially in vertical alinement with the axle of the rear wheel,

and its face upon the opposite side of the frame from the screw G is angled in such manner as to have a plane c' parallel to the 55 brace-rod and a second plane b at a considerable angle, as illustrated in Fig. III, against which is pivotally retained the correspondingly-angled head c of the support, as by a stud E, revolvably mounted in the collar and 60 provided with a squared head E'. The head E' projects beyond the angled face of the collar and enters an inclined-sided aperture in the head c of the support in order to accommodate a slight rocking or tilting of the sup- 65 port-head upon a pintle H, which passes through the head c and the head E' of the stud at right angles to the latter.

The purpose of the abutting angled faces of the support head and collar is to enable 70 the support when in the normal position to lie parallel with and in close proximity to the brace A and to compel it when released and thrown backward to assume a position at a considerable angle to the brace for the pur- 75 pose of constituting a secure support and to bring the center of gravity of the wheel a considerable distance to one side of the wheel.

The angled face of the support-head is pro- 80 duced by simply beveling its extremity beyond the pintle H, so that in either position of the support the side of the head parallel to the supporting-legs lies flat against one of the planes of the angled face of the collar and the direction of the support in conse- 85 quence depends upon the plane against which the head below the bevel abuts. Not only is this cam action efficient in automatically directing the position of the legs with respect to the wheel, but it also constitutes a locking 90 device, inasmuch as the head c must have slight lateral movement during the reversal of the support. It is to accommodate this movement that the pintle connection between the stud and the support-head is employed, 95 the parts being made sufficiently loose to accommodate this slight yielding action, but not to such a degree as to overcome all resistance.

The support may be made of a single rod, but I prefer to employ the construction shown 100 in the drawings, in which a leg C' is hinged, as by a pintle I, within a recess in the head c , from which latter extends a rigid leg C.

The legs C and C' are preferably made semi-

cylindrical and are provided in their adjacent faces with corresponding longitudinal recesses c^2 , within one of which is terminally secured a leaf-spring F, the tendency of which 5 is to force the legs apart, but which, when they are held together, as by the clip-hook D, is entirely concealed. The clip-hook D referred to is adjustable by means of a split collar and clamping-screw G' upon the brace A, and consists of a leaf-spring forming a substantially cylindrical portion and a clip end. The hook 10 is preferably located at the upper extremity of the brace A, and constitutes locking and releasing mechanism for the support immediately under the seat of the bicycle within 15 easy reach of the rider.

By the construction hereinbefore described I am enabled to produce a support for bicycles which is normally carried close against the 20 rear brace of a bicycle and which when released by the rider by forcing its end from the hook D automatically assumes a position at a considerable angle with respect to the wheel and which by the same act is automatically converted into a two-legged supporting-frame.

The purpose of the location of the supporting-collar in vertical alinement with the rear axle is to locate it in alinement with the point 30 from which the wheel swings in the event of the front wheel being turned by accident or design, and thus reducing to the minimum the liability of overthrowing the bicycle in the event of its being jostled.

I do not desire to limit myself to the details of construction herein shown and described, but reserve to myself the right to vary and modify the same at will within the 35 scope of my invention.

What I claim is—

1. The combination with the frame of a bicycle, and a supporting-collar provided with an angled face, of a support having a correspondingly-angled face and a rectangular inclined-sided aperture, a stud revolvably secured to the collar and having a squared head 45 projecting into the rectangular aperture of the support, and a pintle transverse with respect to the stud pivotally securing the support to the squared head of the stud, substantially as specified.

2. In a support for bicycles, the combination with a supporting-collar, of a support pivoted thereto, said collar having two separate and distinct faces upon the opposite sides 55 of the pivot and at an angle with respect to each other, the line of juncture of the faces extending entirely across the collar and diametrical with respect to the pivot, and said support pivoted to the supporting-collar being provided with an angled face corresponding to and adapted to coöperate with the supporting-collar, substantially as set forth.

3. In a support for bicycles, the combination with a supporting-collar having two separate and distinct faces and at an angle to each other, of a revoluble stud projecting from the collar and provided with a squared end, a support provided with an angle end, and with a square, inclined-sided aperture, and a 60 pintle passing transversely through the support and the squared head of the stud, substantially as specified.

In testimony whereof I affix my signature in presence of two witnesses.

DANIEL W. ALBRIGHT.
